UNITED STATES PATENT OFFICE.

HARRY NYQUIST, OF ELMHURST, NEW YORK, ASSIGNOR TO AMERICAN TELEPHONE AND TELEGRAPH COMPANY, A CORPORATION OF NEW YORK.

MEANS FOR INCREASING POWER CAPACITY OF 22-TYPE REPEATERS.

Application filed June 27, 1923. Serial No. 648,069.

To all whom it may concern:

Be it known that I, HARRY NYQUIST, residing at Elmhurst, in the county of Queens and State of New York, have invented certain Improvements in Means for Increasing Power Capacity of 22-Type Repeaters, of which the following is a specification.

This invention relates to improvements in repeater circuits, and more particularly to arrangements for increasing the power capacity of vacuum tube repeater circuits.

When a battery with a fluctuating voltage is utilized to supply potential to the plate circuit of a vacuum tube repeater the gain of the repeater would have a tendency to be irregular as the fluctuating battery would tend to vary the internal impedance of the tube, which in turn would tend to vary its output impedance upon which the gain depends. It has accordingly been the practice to include in the output circuit of the tube a series resistance having an impedance relatively large with respect to the internal impedance of the tube so that the total output impedance would not be varied to any appreciable extent by a variation in the internal impedance of the tube itself. This series resistance, however, will cause an undesirable transmission loss in the circuit. It is in general the object of this invention to obviate the use of this objectionable series resistance, while at the same time increasing the power capacity of the vacuum tube circuit and causing it to operate in a stable manner despite the fact that a supply battery is utilized which may have a fluctuating voltage. The objects of the invention may be accomplished by a novel adjustment and relation of the impedance elements of the circuit which may be more fully understood from the detailed description herein-after given.

The invention may be more fully understood from the following description together with the accompanying drawing in Figures 1, 2, 3, 4, 5, 6 and 7 of which the invention is illustrated. Figs. 1 and 2 illustrate schematically the impedance relations and operating characteristics of arrangements of the prior art, while Fig. 3 shows schematically the impedance relations and operating characteristics of the arrange-

ments of the invention. Figs. 4, 5 and 6 show in detail the circuit arrangements and impedance relations of Figs. 1, 2 and 3 respectively. Similar reference characters have been utilized to denote like parts in all of the figures of the drawing. Fig. 7 is a schematic diagram which accompanies certain mathematical computations given to illustrate the principles of the invention.

In Fig. 1 is shown a circuit including a vacuum tube 1 having grid, filament and plate electrodes. The circuit is connected through a transformer 2 to a line L. In the arrangement shown it will be assumed that steady battery will be utilized for supplying potential to the tube, or in other words, a battery which will not be subject to voltage fluctuations. The internal impedance of the tube will be assumed to be 6000 ohms. The ratio of the transformer 2 will be adjusted so that looking out toward line L the impedance will be 6000 ohms. The potential drop across the output circuit of the tube at points on line 5, 6, will be v which will be $1/2 V$ which is the internal voltage at full load. This will hold true because the impedance looking into the transformer 2 will be 6000 ohms which is $1/2$ of the total series impedance of the plate circuit. By the power capacity of the amplifying arrangements is meant the useful power delivered to the output transformer. This may be expressed as $Iv = RI^2$ where R = the impedance looking into the output transformer, I = the plate current, and V = the applied voltage. From the values assumed heretofore it will be seen that $R = 6000$ ohms, and $v = V/2$ accordingly.

$$I = \frac{V/2}{6000} = \frac{V}{12000}$$

and therefore

$$RI^2 = 6000 \times \frac{V^2}{(12000)^2} = \frac{V^2}{24000}$$

Accordingly the output power capacity of the amplifying circuit in Fig. 1, which may be termed case A, is

$$\frac{V^2}{24000}.$$

In Fig. 2 is shown a tube 1, which may be assumed to be supplied with potential from a battery whose voltage will fluctuate. To prevent the output impedance of the tube from varying materially because of fluctuations in the internal impedance due to the battery fluctuations, there is inserted in series in the plate circuit of the tube a relatively large impedance, such as 12000 ohms, as heretofore explained. The internal impedance of the tube may be taken as approximately 6000 ohms. To avoid reflection losses as will be explained hereinafter the impedance looking out toward the line through the transformer will now be made 18000 ohms by suitable adjustment of the ratio of the transformer. The drop v across the transformer will now be $1/2 V$ as before. The power capacity of the amplifying arrangement will be RI^2 . From the values assumed heretofore it will be seen that

$$R=18000 \text{ ohms}$$

$$v=V/2$$

accordingly

$$I=\frac{V/2}{18000}=\frac{V}{36000}$$

and therefore

$$RI^2=18000 \times \frac{V^2}{(36000)^2}=\frac{V^2}{72000}$$

Accordingly the output power capacity of the amplifying arrangement in Figure 2, which may be termed case B, is $\frac{V^2}{72000}$. It

will be seen that the useful energy of a repeater of this type will be much less than that of Fig. 1.

In the arrangements of the invention, shown schematically in Fig. 3, fluctuating battery supplies the voltage for the tube 1, whose internal impedance is approximately 6000 ohms. The series resistance heretofore included in the plate circuit is omitted but the ratio of the transformer is changed so that the impedance looking into the transformer 2 is increased by the same amount as the series resistance, in other words this impedance is raised from 18000 ohms to 30000 ohms. With these values it will be clear that any variation in the internal impedance of the tube due to voltage fluctuations will cause comparatively little effect due to the fact that the total output impedance is relatively so much larger than the internal tube impedance. With the above impedance values it may be seen that $R=30000$

However v will equal $\frac{5V}{6}$ as the impedance looking into the transformer 2 is 30000 ohms which is $5/6$ of the total impedance

of 36000 ohms of the plate circuit. Accordingly

$$I=\frac{5V/6}{30000}=\frac{V}{36000}$$

and

$$RI^2=30000 \times \frac{V^2}{(36000)^2}=\frac{V^2}{43200}$$

Accordingly it will be seen that the output power capacity of the amplifying arrangement in Fig. 3, which may be termed case C, will be

$$\frac{V^2}{43200}.$$

If we now take the three values thus ascertained for the output power capacity of the amplifiers in cases A, B, and C we will find them to be

$$\frac{V^2}{24000}, \frac{V^2}{72000}, \text{ and } \frac{V^2}{43200}$$

respectively. By reduction the ratio between these values will appear as $\frac{V^2}{5}$ for

A, $\frac{V^2}{15}$ for B, and $\frac{V^2}{9}$ for C. From comparison with the amplifiers in case A, which due to the steady battery will have the greatest power capacity or power output, it will be seen that in case B the amplifier will only have $1/3$ the power capacity or power output of case A while in case C the amplifier will have $5/9$ the energy output of case A. In other words the amplifier in case C will give 1-2/3 times the energy output of the amplifier in case B. In this connection it should be noted that while the arrangements of case A are ideal nevertheless such an arrangement can not be used with fluctuating battery and hence the arrangement of the present invention is of marked advantage where fluctuating plate potentials are employed.

In Figs. 4, 5 and 6, respectively are shown circuit diagrams illustrating the principles of cases A, B and C heretofore described as applied to two way two element repeaters. In each figure the line L and balancing network N are shown having an impedance of 1800 ohms, for purposes of illustration. The line L includes a three winding transformer 2. Connected to one of the windings of the transformer is the output of a vacuum tube 1 and included in a circuit bridged across the mid-points of windings of the transformer is a potentiometer 7, a transformer 8, and the input of a vacuum tube 9. The output of the tubes 1 and 9 may be assumed to have internal impedances of approximately 6000 ohms. In Fig. 4, as in Fig. 1, the ratio of the transformer 2 will be adjusted so that its impedance looking out into line L and artificial line N will be

6000 ohms. The impedances of 1800 ohms, each of line L and network N are connected in series and hence with respect to amplifier 1, the transformer 2 will operate to step 3600 ohms up to 6000 ohms. The ratio of transformation between the tube 1 and the other impedance of the plate circuit will be 6000 ohms to 6000 ohms as viewed at points on line 5, 6.

10 In other words the impedances looking in both directions at a point such as on line 5, 6, will be equal. The impedance at points 10-11 looking into the line will be 900 ohms as the impedances of 1800 ohms each of the line and network in this respect are connected in parallel. Accordingly the impedance looking into the potentiometer will be made to match this so that the impedance ratio across line 10, 11 will be the same as 15 the ratio across line 5, 6. In other words the impedance looking in both directions at a point such as on line 10, 11 will be equal. Under these conditions the passive impedance of the whole repeater will be substantially equal to that of the line as indicated at line 3, 4 and there will be no reflection loss. The reasons for this and the impedance value to be given the potentiometer under various conditions will appear more fully from the mathematical discussion to be 20 given hereinafter.

25

30

In Fig. 5, as in Fig. 2, the ratio of the transformer 2 will be adjusted so that the impedance looking out into the line L and artificial line N will be 18000 ohms. The impedances of 1800 ohms each of line L and network N are connected in series with respect to amplifier 1 and hence the transformer 2 will operate to step 3600 ohms up to 18000 ohms. The ratio of transformation between the combined impedance of tube 1 and resistance 13 and the other impedance of the plate circuit will be 18000 ohms to 18000 ohms as viewed at points on line 5, 6. In other words the impedances looking both ways at a point such as on line 5, 6, will be equal. The impedance at points 10—11 looking into the line and network will be 900 ohms as the impedances of 1800 ohms each of the line and network in this respect are connected in parallel. Accordingly the impedance looking into the potentiometer will be made to match this so that the impedance ratio across line 10, 11 will be the same as the ratio across line 5, 6. In other words the impedance looking in both directions at a point on line 10, 11 will be equal. Under these conditions the passive impedance of the whole repeater will be substantially equal to that of the line as indicated at line 3, 4 and there will be no reflection loss. The reasons for this and the impedance value to be given the potentiometer under various conditions will appear more fully from the mathematical discussion to be given hereinafter.

In the arrangements of the invention shown in Fig. 6, as well as Fig. 3, the ratio of the transformer 2 will be adjusted so that its impedance looking out into the line L and network N will be 30000 ohms. The impedances of 1800 ohms each of line L and network N are connected in series and hence with respect to amplifier 1 the transformer 2 will operate to step 3600 ohms up to 30000 ohms. The ratio of transformation between the impedance of tube 1 and the other impedance of the plate circuit will be 6000 ohms of 30000 ohms as viewed at a point such as line 5, 6. In other words the impedances looking both ways at a point such as line 5, 6 will not be matched or equal but will be unequal. The impedance looking out from the potentiometer 7 into the line and network will still be 900 ohms as the impedances of 1800 ohms each of the line and network in this respect are connected in parallel. In order to compensate for the impedance irregularity at points 5-6 of the output circuit of tube 1, a similar irregularity should be introduced at points 10-11 and accordingly the impedance looking into the transformer will in this instance be made 4500 ohms. Under these conditions the passive impedance of the repeater will be substantially equal to that of the line as indicated at 3, 4, and there will be no reflection loss at this point. The reasons for this will appear from the following mathematical discussion.

In connection with Fig. 7 there are given some computations on the passive impedance of a two way two element repeater on the assumption the impedances of the tubes, balancing network and the potentiometer may have arbitrary values. More specifically the computations are given so that it may be determined what impedance should be given to the potentiometer in order to have the passive impedance of the repeater substantially equal to the line impedance when the balancing network is made equal to the line impedance and the ratio of transformation between the tube impedance and the other impedances is altered from the usual value as in Fig. 6. In the arrangements of Fig. 7 it is assumed that the hybrid coil is symmetrical. Z_4 represents the impedance of the tube 1, Z_3 the impedance of the potentiometer 7, and Z_2 that of the balancing network; n is the ratio of the number of turns in the tube circuit to the total number of turns on all the other windings. I_1 , I_2 , I_3 and I_4 are the currents in the parts of the network indicated in the figure. e represents the voltage across one half of the line windings, as indicated. E_1 is the voltage impressed on the network. It will be apparent that the passive impedance Z'_1 equals E_1 / I_1 . The procedure to determine this ratio 130

will be to set up simultaneous equations relating the quantities E_1 , e , I_1 , I_2 , I_3 and I_4 , and to eliminate all these quantities except E_1 and I_1 . The ratio can then be determined 5 immediately from the resulting equation.

From an inspection of Fig. 7 it will be apparent that the following relations may be written down:

$$18 \quad I_1 = I_2 + I_3 \quad (1)$$

$$I_4 = \frac{I_1 + I_2}{2n} \quad (2)$$

$$15 \quad e = \frac{I_1 Z_4}{2n} \quad (3)$$

$$E_1 = e + I_3 Z_3 \quad (4)$$

$$I_3 Z_3 = e + I_2 Z_2 \quad (5)$$

20 This gives a total of five equations between six unknown and hence by ordinary algebra four of six unknown can be eliminated, leaving a relation between E_1 and I_1 . Solving this relation gives for the passive impedance

$$25 \quad Z'_1 = \frac{E_1}{I_1} = \frac{Z_2 Z_3 + \frac{Z_2 Z_4}{4n^2} + \frac{Z_3 Z_4}{n^2}}{Z_2 + Z_3 + \frac{Z_4}{4n^2}} \quad (6)$$

30 To apply the above computations to a solution of the problem presented by one of the figures, such as Fig. 6, namely to determine how the impedance Z_3 of the potentiometer should be chosen to make the passive impedance of the repeater equal to the line impedance when the ratio of the transformer is changed, the procedure is as follows: Assuming that $Z_4 = 6000$ and that 35 Z_2 equals the characteristic impedance of the line, termed Z , it is seen that the requirement amounts to making $Z'_1 = Z = Z_2$. Substituting in equation (6) above and solving 40 we have

$$45 \quad Z_3 = \frac{Z^2 n^2}{6000} \quad (7)$$

If $Z = 1800$ and

$$50 \quad n^2 = \frac{30000}{3600}$$

(which is the value it would have to have

to make line and network look like 30000) this becomes

$$55 \quad Z_3 = \frac{1800^2 \times 30000}{6000 \times 3600}$$

$$= \frac{18^2 \times 3000}{6 \times 36}$$

$$= 4500$$

Accordingly the impedance of the potentiometer, as has been pointed out, is made equal to 4500 ohms in Fig. 6.

While the arrangements of the invention 60 have been disclosed in certain specific arrangements which are deemed desirable, it is understood that they are capable of embodiment in many and widely varied forms without departing from the spirit of the invention as defined in the appended claims.

What is claimed is:

1. A two element two way repeater circuit comprising a line, an amplifier having its output circuit transmitting to the line through a hybrid coil whose ratio is adjusted to make the impedance looking into the coil large as compared with the impedance looking into the amplifier, a second amplifier having its input circuit arranged 75 for transmitting from the line to the amplifier, and means to make the impedance looking into the input circuit of said second amplifier large as compared with the impedance looking toward the line in order 80 to compensate for the impedance irregularity in the output circuit of the first amplifier.

2. A two element two way repeater circuit comprising a line, an amplifier having 90 its output circuit associated with the line through a hybrid coil, means for introducing an impedance irregularity in said output circuit, a second amplifier having its input circuit arranged for transmitting from 95 the line to the amplifier, means for introducing an impedance irregularity in said input circuit to counteract the impedance irregularity introduced in said output circuit of said first mentioned amplifier.

In testimony whereof, I have signed my name to this specification this 26th day of June, 1923.

HARRY NYQUIST.
